FISHING PLUG CASTING DEVICE

Jess A. Johnson, Bryan, Tex.

Application November 15, 1957; Serial No. 696,657

4 Claims. (Cl. 43—19)

This invention relates to a fishing plug casting device, and it concerns more particularly a piston-actuated device, operable by gas pressure acting upon the piston, capable of catapulting a plug loosely supported on the device in response to the movement of the piston.

The invention will be readily understood by referring to the following description and the accompanying drawing, in which:

Figure 1 is a longitudinal view of a fishing plug casting device embodying the invention, showing partly in section, taken on a median line, a plug attached to the casting device in firing position;

Figure 2 is a fragmentary longitudinal view, partly in section taken on a median line, of a portion of the apparatus shown in Figure 1, showing the manner in which the plug is reeled in, on the end of the fishing line, whereby it automatically attaches itself to the casting device in firing position;

Figure 3 is a fragmentary longitudinal view, partly in section taken on a median line, showing another form of plug and means for attaching the plug to the casting device;

Figure 4 is a fragmentary longitudinal view, partly in section taken on a median line, showing another form of plug and means for attaching the plug to the casting device;

Figure 5 is a transverse view, partly in section, showing a holder for another form of plug attached to the casting device;

Figure 6 is a fragmentary longitudinal view, partly in section taken on the lines 6—6 of Figure 5, showing a plug supported upon the holder and attached to the casting device in firing position;

Figure 7 is a fragmentary longitudinal view, partly in section taken on a median line, showing a plug supported upon another form of holder and attached to the casting device;

Figure 8 is a longitudinal view, partly in section taken on a median line, of the casting device;

Figure 9 is a transverse sectional view, on an enlarged scale, taken on the lines 9—9 of Figure 8;

Figure 10 is a transverse sectional view, on an enlarged scale, taken on the lines 10—10 of Figure 8; and

Figure 11 is a transverse sectional view, on an enlarged scale, taken on the lines 11—11 of Figure 8.

Referring to the drawing, the casting device of the invention includes an elongated tubular housing, which is designated generally by the numeral 1. The housing 1 is formed by a pair of elongated tubular members, numbered 2 and 3, which are arranged end to end and connected by a tubular connecting member 4.

The tubular member 3 is of smaller diameter than the tubular member 2, and is positioned eccentrically relative thereto. The connecting member 4 is enlarged internally and externally intermediate its ends to conform to the relative sizes of the tubular members 2 and 3. The connecting member 4 is externally threaded at 5 for

engagement by the tubular member 2, and is internally threaded at 6 for engagement by the tubular member 3.

The connecting member 4 forms a partial closure for one end of the tubular member 2, and its opposite end is closed by an externally threaded plug 7. The plug 7 has a normally closed threaded opening and a check valve incorporated therein, whereby it may be connected to a source of compressed gas, such as carbon dioxide, which is to be introduced into the tubular member 2 for use as 10 a propellant for the casting device. Plugs of the type described are commonly used in small arms, for example, for the introduction of compressed gas.

A cylindrical plug 8 is positioned in the tubular member 2 intermediate its ends, and is secured therein by 15 friction fit. The space within the tubular member 2 between the plugs 7 and 8 forms a storage chamber for compressed gas. A fluid passage 9 is formed in the plug 8 and extends through it diagonally from one end to the other. The fluid passage 9 terminates at one end in a 20 threaded opening 10, which is formed in the plug 8 opposite the connecting member 4, and in alignment with the tubular member 3. The opposite end of the fluid passage 9 terminates in a valved opening 11 which is positioned eccentrically of the plug 8 opposite the plug 7.

25 An elongated cylinder 12, which has a piston 13 reciprocable therein, is positioned eccentrically within the tubular member 2 and the connecting member 4, and is externally threaded at one end for engagement with the threaded opening 10 of the plug 8. The opposite end of 30 the cylinder 12 is received in the adjacent end of the tubular member 3.

A valve disc 14, which is normally seated in the opening 11 of the plug 8, is connected to one end of a valve stem 15, which extends through an opening provided 35 therefor in the plug 8, parallel to the cylinder 12. A compression spring 16, which surrounds the end of the valve stem 15 opposite the valve disc 14, acts upon the plug 8 and the adjacent end of the valve stem 15 to yieldably urge the valve disc 14 in engagement with its seat. 40 The valve disc 14 is normally seated in the opening 11 due to the pressure differential on opposite sides thereof, so that the spring 16 may be omitted if desired.

The arrangement is such that compressed gas is admitted to the cylinder 12, through the fluid passage 9, to 45 thereby actuate the piston 13, upon moving the valve stem 15 to the left, as shown in Figure 8, to thereby unseat the valve disc 14. The speed with which the piston 13 is propelled through the cylinder 12, which determines the distance which the plug is catapulted from the casting device, as hereinafter described, varies directly with the initial force which is applied to the valve stem 15 to unseat the valve disc 14, which controls the degree of opening of the valve disc 14 as well as the speed with which it is opened. It is desirable that the valve disc 14 be 50 opened instantly and to a degree sufficient to supply momentarily the gas pressure necessary to actuate the piston 13. Thereafter the valve disc 14 should be closed quickly, to conserve gas.

55 The outside diameter of the cylinder 12 is reduced intermediate its ends to form an external shoulder 17 facing the plug 8. A cylindrical element 18, which is received in the tubular member 2 and slidably engages the inner wall thereof, has an eccentric bore 19 which surrounds, and slidably engages the cylinder 12. The bore 19 is enlarged intermediate its ends to form an internal shoulder 20 facing the external shoulder 17 of the cylinder 12. A compression spring 21, which surrounds the cylinder 12 and is disposed partly in the bore 19 of the element 18, acts upon the opposed shoulders 17 and 20 60 whereby a longitudinal thrust is imparted to the element 18, to advance it relative to the plug 8 and the valve stem 15, to thereby open the valve 14, upon compressing the 65

spring 21, by advancing the element 18 relative thereto, and thereafter releasing the element 18.

A plurality of longitudinally spaced annular grooves 22 are formed in the peripheral surface of the cylindrical element 18 for selective engagement by a detent formed on one end of a lever 23, whereby the spring 21 may be compressed to a greater or less degree, by advancing the element 18 a predetermined distance relative thereto, and the element 18 may be latched in its selected position to retain the spring 21 in its compressed condition. The casting device is fired by manipulation of the lever 23, as hereinafter described, whereby the element 18 is released.

The tubular member 2 forms the handle of the casting device. An elongated hollow body 24, which is connected to one side of the tubular member 2, provides a support for a reel, designated generally by the numeral 25, which is removably connected thereto.

The lever 23 is disposed partly in the hollow body 24, and is pivotally connected thereto by a pin 26. The pin 26 is connected at its ends to the sides of the body 24. A coil spring 27, which surrounds the pin 26, acts upon the lever 23 and the body 24 to yieldably urge the detent, which is formed on one end of the lever 23 and extends through an opening provided therefor in the tubular member 2, in engagement with one of the annular grooves 22 of the element 18. The opposite end of the lever 23 extends outwardly beyond one end of the body 24, and has a finger grip formed thereon for use in latching and releasing the element 18.

As shown in Figure 1, a finger grip 28 is attached to one side of the element 18, and extends outwardly therefrom, at right angles to the lever 23, through a longitudinal slot 29 formed in the tubular member 2. A finger grip 30, for use in conjunction with the finger grip 28 to advance the element 18 relative to the spring 21, is attached to the side of the tubular member 2 adjacent one end of the slot 29.

A plug 31, which has a central bore 32 therein, is externally threaded at one end, as at 33, for engagement by the end of the tubular member 3 opposite the connecting member 4. An elongated rod 34, which is received in the bore 32 of the plug 31, is disposed partly in the tubular member 3 and extends outwardly beyond the plug 31.

An elongated rod 35, which is substantially coextensive with the cylinder 12, is connected at one end to the piston 13 whereby the rod 35 is reciprocable in the cylinder 12. The rod 35 is connected at its opposite end, by a coupling 36, to a stem 37 which is formed integrally with the adjacent end of the rod 34.

A compression spring 38, which surrounds the stem 37, acts upon a flange 39 formed on the adjacent end of the coupling 36, and a washer 40 surrounding the stem 37 and positioned between the spring 38 and a shoulder formed by the adjacent end of the rod 34, to absorb shock upon impact of the washer 40 against the plug 31, which limits longitudinal movement of the rods 34 and 35 in response to gas pressure acting upon the piston 13.

A lug 41 extends radially inwardly from the wall of the bore 32, adjacent the outer extremity of the plug 31, for engagement with a longitudinal groove 42 formed in the rod 34, to prevent the rod 34 from turning.

A fitting 43, which is attached to the outer end of the rod 34 and forms an extension thereof, is externally threaded at its outer end, as at 44, and has a central bore 45 formed therein, beginning at its outer end. The bore 45 communicates at its inner end with an inclined passage 46 formed in one side of the fitting 43 intermediate its ends.

The several plugs shown in Figures 1 to 7 are each attachable to the fitting 43, as hereinafter described. A fishing line 47, which is wound upon the reel 25 and connected at one end to one of the plugs, is passed through the bore 45 and the passage 46 of the fitting 43 whereby

the plug is capable of attaching itself to the fitting 43 upon reeling in the line 47. An eye 48 is attached to the outer end of the tubular member 3 for engagement by an intermediate portion of the line 47.

5 The plug shown in Figures 1 and 2 has a body 49 having a central bore 50 formed therein, beginning at one end thereof, adapted to be received on the outer end of the fitting 43. A swivel 51, which is secured in the bore 50, is attached to the adjacent end of the line 47, so that upon 10 reeling in the line 47 the plug is capable of attaching itself to the fitting 43.

The plug shown in Figure 3 has a body 52 having a screw 53 inserted in one end thereof. A pin 54, which is receivable in the bore 45 of the fitting 43, is connected 15 by a swivel 55 to the outer end of the screw 53. The opposite end of the pin 54 is attached to the adjacent end of the line 47.

The plug shown in Figure 4 has a body 56 having a screw 57 inserted in one end thereof. A pin 58, which is receivable in the bore 45 of the fitting 43, 20 comprises an outward extension of the screw 57, The outer end of the pin 58 is attached to the adjacent end of the line 47.

The plug shown in Figure 6 has a body 59 which is pivotally connected at one end to one end of a pin 25 60, which is receivable in the bore 45 of the fitting 43. The opposite end of the pin 60 is attached to the adjacent end of the line 47. The body 59 is suspended from its connected end, and is additionally supported upon a spoon shaped holder 61, which is rigidly connected 30 at its upper end, by a bracket 62, to an internally threaded tubular fitting 63 which is attached to the outer end of the fitting 43.

The plug shown in Figure 7 has a body 64 which is supported upon a spoon shaped holder 65. The holder 35 65 is rigidly connected intermediate its ends, by an internally threaded tubular portion 66 formed integrally therewith, to the outer end of the fitting 43. The body 64 is pivotally connected at one end to one end of a pin 67, which is receivable in a sleeve 68 rigidly connected 40 to the upper end of the holder 65. The body 64 is suspended from its connected end, and is additionally supported upon the holder 65. The opposite end of the pin 67 is attached to the adjacent end of the line 47.

In each of the arrangements shown in Figures 1 to 45 4, upon firing the casting device a longitudinal thrust is imparted by the fitting 43 to a plug supported upon the fitting 43 in longitudinal alignment therewith and abutting relationship thereto, to thereby catapult the plug from the casting device. In the arrangements 50 shown in Figures 5 to 7 the longitudinal thrust is imparted to a holder for the plug, which is positioned transversely relative to the fitting 43 in abutting relationship to the side of the plug. The arrangements shown in Figures 5 to 7 are particularly useful in connection with the smaller plugs.

The invention may be modified in various ways without departing from the spirit and scope thereof.

What is claimed is:

1. A fishing plug casting device comprising a tubular housing having a gas chamber in one end thereof for the storage of gas under pressure, a first plug in the adjacent end of the housing forming a closure therefor and having a valved opening therein for the introduction of gas under pressure, a second plug in the housing intermediate its ends defining the gas chamber, an elongated cylinder in the housing communicating with the gas chamber through a fluid passage extending diagonally through the second plug and terminating in 65 openings in opposite ends of the plug spaced laterally relative to each other, a valve in the gas chamber adapted to be seated in the opening in the adjacent end of the second plug, a valve stem having one of its ends connected to the valve and extending through an opening 70 therefor in the second plug, in parallel relation to 75 the bore 45 and the passage 46 of the fitting 43 whereby

the cylinder, the valve being normally closed due to the pressure differential on opposite sides thereof, a cylindrical element in the housing surrounding and slidably engaging the cylinder, the cylindrical element having a plurality of longitudinally spaced annular grooves in its peripheral surface, a compression spring surrounding the cylinder and acting upon the cylindrical element and the cylinder to advance the cylindrical element relative to the valve stem, to open the valve, upon advancing the cylindrical element relative to the spring, to compress the spring, and thereafter releasing the cylindrical element, a spring biased lever pivotally connected intermediate its ends to the housing, exteriorly thereof, and having a detent on one of its ends extending through an opening therefor in the housing and capable of selectively and releasably engaging one of the annular grooves of the cylindrical element whereby the cylindrical element is retained in one of several advanced positions relative to the spring, a finger grip on the cylindrical element and operable outside the housing to advance the cylindrical element relative to the spring, a piston reciprocable in the cylinder, a first rod substantially co-extensive with the cylinder and connected at one end to the piston, a second rod connected to the opposite end of the first rod and extending outwardly beyond the end of the housing opposite the first plug, the outwardly extending portion of the second rod being adapted to engage a fishing plug and cast it in response to the action of gas pressure acting on the piston, a third plug in the adjacent end of the housing surrounding the second rod, and resilient means on the

rods for engagement with the third plug to limit the longitudinally outward movement of the rods.

2. In combination with a fishing plug casting device as described in claim 1, a fitting on the outer end of the second rod capable of loosely supporting a fishing plug in abutting relationship thereto.

10 3. In combination with a fishing plug casting device as described in claim 1, a fishing plug, a fishing line connected at one end to the plug, a reel for the line operatively connected to the housing, and a fitting on the outer end of the second rod for engagement by the plug and capable of loosely supporting the plug in abutting relation thereto, the fitting having a passage therein for the line and the plug having means coacting with the fitting whereby the plug is adapted to be supported on the fitting, in firing position, upon reeling in the line.

15 4. In combination with a fishing plug casting device as described in claim 1, a fishing plug, a fishing line connected at one end to the plug, a reel for the line operatively connected to the housing, and means loosely supporting the plug on the outer end of the second rod in abutting relation thereto.
